Attorney.

UNITED STATES PATENT OFFICE.

ALFRED AUGUSTUS THOMAS CRESER, OF RICHMOND, ENGLAND.

CARBURETOR.

Application filed March 12, 1925, Serial No. 15,042, and in Great Britain March 18, 1924.

This invention relates to improvements in carburetors for use with internal combustion engines.

In these carburetors it is known to employ a slideable piston-valve or block formed with a choke tube for each main nozzle, the choke tubes extending directly through the piston-valve or block and being lowered upon each of the main nozzles simultaneously so that the said nozzles are equally uncovered or controlled.

According to the present invention, I form the sliding block which contains the choke tubes, in such a way that it can be moved backwards and forwards across a chamber into which the main nozzles project, and in such a way that the sliding block and the choke tubes therein are at right angles to the axes of the said nozzles. The sliding block is preferably of rectangular cross section. The choke tubes are slotted to accommodate the nozzles in this movement and these slots extend almost up to the contracted throat portions of such choke tubes.

The rectangular cross-section of the sliding block allows in a given area a larger number of choke tubes than does the same area of a circular cross section of a cylindrical piston valve and further, the horizontal arrangement of the sliding block with horizontal choke tubes passing across the upstanding main nozzles, enables me to obtain a straight-through passage for the indrawn air, with the minimum impeding of or restriction to the flow of air or "mixture."

The present invention is hereafter described with reference to the annexed drawings in which:

Figure 1 is a plan of the bridge carrying the main nozzles and idling nozzle.

Figure 2 is a section on line 2-2 of Figure 3.

Figure 3 is a plan view with cover plate removed and sliding block in part section.

Figure 4 is an elevation of the rectangular sliding block, and Figure 5 is a plan view of the said sliding block in its box with the box lid removed.

Figure 6 is a diagram showing a suitable device for operating the sliding block.

Figure 7 is a diagram of the Venturi tube showing the position of the throat relative to the nozzle.

Figure 8 is a side elevation of the improved carburetor.

Between the air intake *a* formed upon the body *A* of the carburetor and the flange fitting *b* whereby the carburetor is adapted to be attached to the engine, is arranged horizontally a shallow box *c* of rectangular shape in horizontal and vertical sections. This box *c* is provided with a detachable lid *d* having a longitudinal slot *d*¹ therein. This lid may be secured to the box by screws *d*² at the corners. The box is arranged to be carried upon a bridge *E* comprising hollow arms *e* *e*¹ extending laterally from the float chamber *f*¹. By means of flanges *f* *f*¹ and screws the box portion *q* can be detachably secured to the lateral arms of the bridge. The hollow arms *e* *e*¹ forming the bridge are closed at their outer ends by screws.

The float chamber *f*¹ is of any convenient construction and may comprise the usual float with needle valve for controlling the supply of gasoline to the chamber *f*¹.

From below the box *c* and in such a way that they are in communication with the lateral arm *e* supplied with fuel from the float chamber *f*¹, extend a number of nozzle tubes or main nozzles *h* *h* *h* aligned across the box *c* and upstanding through and above the bottom of the said box. The rectangular sliding block shown at *i* covers these main nozzles *h* and is provided with a corresponding number of Venturi tubes *j* bored horizontally through said sliding block *i*. These Venturi tubes are also slotted at *k* on their under portions (see Figure 4), the open ended slots *k* extending from the inlet on the intake side (right hand side of Figure 3) almost up to the throats of the tubes so that the main nozzle tubes or nozzles *h* enter the tubes at right angles to the axes of the horizontal bores through said sliding block when the latter is moved to the right, to the limit of its movement. These nozzles *109*

h extend preferably up to the center lines of the bores of the Venturi tubes.

The sliding block *i* has a stud *l* passing up through the slot *d*¹ in the lid *d* and through a slidible strip *m* which moves with the stud *l* and at all times covers the slot *d*¹. This strip is of metal and guided in its longitudinal movements by the ribs *d*³ on the lid *d*. The stud *l* is acted on in one direction by, for example, a coiled spring *n* and in the other direction a flexible connection such as the well known Bowden wire represented diagrammatically at *o*, Figure 6, passing through guide *s*. Any other suitable device however, may be provided for adjusting the position of the slidible block *i* relatively to the main nozzles *h*, and for the easy movement of such slidible block.

20 The block-containing box *c* is preferably cast in one piece with the air intake *a* and with the flange fitting *b*. The latter may be of any desired contruction and is bored at *b*¹ to provide an outlet for the "mixture", so that a straight-through passage for air or "mixture" can be obtained with a minimum hindrance by reason of the Venturi tubes *j* in the rectangular-sectioned sliding block *i*. The air intake *a*, the chamber *c*, the Venturi tubes *j* and the mixture outlet *b*¹ are aligned.

25 The Venturi tubes are so tapered from the inner ends of the slots *k*, that at no point is the cross sectional area of the tubes, minus the space occupied by the nozzle tube or nozzle *h*, less than the cross sectional area at the throat.

30 Referring to Figure 7, the cross sectional area at *x* (less the nozzle) is never less than the cross sectional area at *y*.

35 40 An idling nozzle is indicated at *p* delivering into the bore *b*¹ and a butterfly throttle valve at *q*, this valve *q* being of any well known construction, pivoted in the inlet to the body *A* and regulated by an external lever *r*.

45 I claim:—

1. A carburetor comprising a body formed as a shallow box chamber of rectangular cross section, said chamber having an air inlet and a mixture outlet and having, apertures in the bottom of said box chamber, a single sliding block movable backwards and forwards in said chamber and also of rectangular cross section, a detachable lid to said box chamber having a slot, a stud upstanding from said sliding block and travelling in said slot in the lid, a supporting bridge for the box chamber, said bridge including hollow arms in communication with a fuel supply chamber, means for detachably securing said box chamber to said supporting bridge, a plurality of nozzle tubes mounted upon one of said bridge-arms and supplied with fuel therefrom, said nozzle tubes up-

standing into said box chamber through the 65 apertures in the bottom of said box chamber and being alined across the box chamber, said single block having a separate Venturi tube formed therein for each of said nozzle tubes, and an open-ended slot on the underside of 70 each said Venturi tube, through which slots and nozzle tubes pass, said tube-provided and slotted sliding block being arranged in advance of said nozzle tubes and being adapted to be drawn back towards the nozzle tubes 75 so that the latter enter the said open-ended slots in the rectangularly shaped sliding block.

2. A carburetor comprising a shallow box chamber of rectangular cross section, said chamber having an air inlet and a mixture outlet, a sliding block of rectangular cross section fitting said chamber and movable therein, a supporting bridge upon which said box chamber is detachably mounted in a horizontal position, nozzle tubes mounted upon said bridge, means for supplying said nozzle tubes with liquid fuel, there being apertures in the base of said box chamber through which said nozzle tubes project, a 80 Venturi tube bored horizontally in said sliding block for each of said nozzle tubes, said Venturi tubes having slots upon their underside extending almost up to the throats of the said Venturi tubes, to permit the passage of said nozzle tubes, said slots having open ends and extending to the rear of said multibored sliding block, said Venturi tubes being so tapered from the inner ends of the slots that at no point is the cross-sectional 85 area of the tube minus the space occupied by the nozzle tube, less than the cross-sectional area of the throat of the Venturi tube, and said air intake, box chamber, and said multi-bored sliding block being alined with respect to each other to afford a horizontal straight-through passage for the air and mixture.

3. A multi-nozzle carburetor comprising in combination, a shallow, rectangularly sectioned box chamber having an air inlet and mixture outlet all cast in one piece, and having apertures in the base of said box chamber, a detachable lid to said chamber having a slot, a sliding block of rectangular section fitted in said box chamber and movable backwards and forwards therein, said rectangular block having a stud travelling in the slot in said lid, a slidible strip carried by said stud and covering the slot in said lid, Venturi tubes bored in said block from front to rear thereof with their axes parallel with the line of movement of said block, said Venturi tubes having longitudinal, open-ended slots upon their underside extending forwardly from the rear of said block, a float chamber, a supporting bridge having hollow arms, said arms being supplied with fuel from said float chamber, said

bridge maintaining said box chamber and sliding block in a horizontal position, main nozzles mounted upon one of said hollow arms and supplied from the interior of said 5 hollow arm, said main nozzles extending through the base apertures in the box chamber and through the slots in the walls of said

Venturi tubes, and means for drawing said sliding block towards the said main nozzles so that the latter can enter said open-ended 10 slots.

In testimony whereof I hereunto affix my signature.

ALFRED AUGUSTUS THOMAS CRESER.
